S. WEINBERG,
ADJUSTABLE SUPPORTING BRACKET,
APPLICATION FILED MAR. 17, 1915.

1,163,797.

Patented Dec. 14, 1915.

Inventor

S. WEINBERG

By *Watson E. Coleman*

Attorney.

UNITED STATES PATENT OFFICE.

SAMUEL WEINBERG, OF SCRANTON, PENNSYLVANIA.

ADJUSTABLE SUPPORTING-BRACKET.

1,163,797.

Specification of Letters Patent. Patented Dec. 14, 1915.

Application filed March 17, 1915. Serial No. 15,145.

To all whom it may concern:

Be it known that I, SAMUEL WEINBERG, a citizen of the United States, residing at Scranton, in the county of Lackawanna and State of Pennsylvania, have invented certain new and useful Improvements in Adjustable Supporting-Brackets, of which the following is a specification, reference being had to the accompanying drawings.

10 My invention relates to means for supporting shelves, doors, closures, and like elements, and particularly to supporting means which will support the movable element such as a door, shelf, etc., either in a horizontal plane or lowered into a vertical plane, and which acts, therefore, in a general way, as a hinge.

15 The primary object of my invention is the provision of a very simple, cheaply made, and readily applied device of this character, which is thoroughly effective in action and gives ample support to the movable element when raised.

20 A further object of my invention is the provision of coacting hinge and supporting members, one of which is provided with a flat-sided lug and the other with a slot or opening angular in form in which said lug slides upon a movement of the first-named element under proper manipulation.

25 Other objects will appear in the course of the following description.

My invention is illustrated in the accompanying drawings, wherein:

30 Figure 1 is a front view of the upper portion of a range showing the warming chamber of the range and the door or closure for said warming chamber; Fig. 2 is an enlarged sectional view through the warming chamber of the range shown in Fig. 1, showing my invention applied to the door or closure therefor, the closure or door being in a vertical position; Fig. 3 is a like view to Fig. 2, but showing the door in its raised or horizontal position; Fig. 4 is a perspective detail view of the two coacting elements which form one of the hinges, as it may be termed, for the closure illustrated in Figs. 1 and 2; Fig. 5 is a sectional view showing my supporting device applied to the shelf.

35 In Figs. 1, 2, 3 and 4, I have shown my device as applied to supporting the door or closure of the warming chamber of an ordinary range. This is purely illustrative of one of the applications of my invention, and I do not wish to be limited to this as the

device may be applied to other constructions without any change in principle.

Referring to Figs. 1, 2, 3 and 4, A designates a frame adapted to be applied or attached to the rear end of a range, and having the brackets *a* which support the usual warming chamber B. The door or closure for this warming chamber is designated 2, and this door is ordinarily hingedly mounted at its upper end so that the door may swing upward to permit access to the warming chamber, and means are usually provided for supporting this door in a horizontal position. The means ordinarily provided are, relatively speaking, complicated and are not entirely effective inasmuch as they do not positively lock the door in its raised position, and as a consequence the door sometimes falls from the hand of the user thus interfering with the manipulation of the food disposed in the heating chamber, besides bruising the hands of the operator.

40 As before stated, the primary purpose of my invention is to provide means for hingedly supporting this door or closure 2 so that it may be raised in a vertical plane, and likewise provide means for readily locking this door in its elevated position, that is, the position shown in Fig. 3. To this end I attach 45 at opposite ends of the chamber B supporting elements one of which is illustrated in Fig. 4 and designated 3. This supporting element, when applied to the heating chamber of a range, is provided with a shank 4 which is bolted or otherwise attached to the downwardly depending flange 5 of the casting of the warming chamber. The lower or depending end of this shank 4 is enlarged to form a head 6, this head having in it the substantially right angular slot 7. The two arms of this slot are disposed at a slightly greater angle than a right angle, as shown most clearly in Fig. 2, and the metal at the intersection of the arms may be cut away, 50 to leave a greater clearance space. As before remarked, there are two of these supporting members 3 disposed one at each end of the chamber 2. Attached to each end of the closure 2, which is ordinarily formed of sheet metal, are the supporting strips 9, each

55 having projecting from one end thereof the integral lug 10. This lug projects laterally from the supporting strip and projects beyond the strip 9 a distance equal to the width of the member 3. Each of the lugs 10 projects into the slot 7 of the correspond-

ing supporting member 3. It will be noted from the drawing that the distance between the lower wall and the upper wall at the junction of the arms 7^a and 7^b is slightly greater than the width of the arms of the slot, and it will also be noted that the upper face of the lug is rounded at the corners. This permits the easy turning of the lug within the slot 7 after the lug has been brought to the point of intersection between the arms of the slot, and thus no binding of the parts on each other can occur. This permits the closure to be readily moved to its raised or lowered position.

15 The operation of the device will be readily seen from Figs. 2 and 3. As before remarked, the slot 7 has two arms or branches, designated in Fig. 4 as 7^a and 7^b. When the door is closed the lugs 10 are disposed 20 in the branch or arm 7^b and the door is supported in a depending position. Inasmuch as the lug 10 is rectangular in section and has a thickness equal to the depth of the slot 7, it is obvious that the door cannot turn 25 when in its depending position with relation to the supporting members. In order to raise the door the door must be pushed upward until the lugs are carried into the upper portion of the slot and then the free 30 end of the door may be raised so as to bring the door into a horizontal position and the door is then shoved backward until each lug is carried into the rear end of the slot, that is, into the arm 7^a. When this occurs, 35 as illustrated in Fig. 3, the rectangular form of the lug, causing the engagement of the lugs with the walls of the arms 7^a, will hold the door in its horizontal position. The door now cannot be accidentally knocked 40 down or lowered in any manner until the door is drawn forward. When the door is drawn forward so as to carry the lugs 10 into the space above the arm 7^a the lug may be rotated within the slot and the door lowered to its depending position. The wall 45 of the slot 7 may be slightly cut away or thinned at 8 so as to permit a free rotation of the lug from a horizontal to a vertical position so that it may readily pass from one arm of the slot into the other arm.

50 It will be obvious that my supporting device may be used not only for ranges, as illustrated in Figs. 1 to 4, but that it may also be used for supporting shelves or any 55 movable element which is intended to be shifted from a vertical position to a horizontal position and in a manner locked in either of these positions. Thus, in Fig. 5, I illustrate my device as applied to the support of a shelf.

60 In this figure 11 designates the shelf and 12

the supporting members, corresponding to the members 3. These supporting members, as illustrated, are each provided with a base 13 which is adapted to be fastened to a wall or other support and with a head 14 which is formed with the angularly disposed slot 15 corresponding to the slot 7 previously described. The shelf 11 is provided adjacent its rear edge and its ends with the outwardly projecting pintle lugs 16. These lugs are arranged in a plane at an angle to the plane of the shelf 11 so that when the lugs 16 are in their rearmost position in the slot 15 the shelf will be supported in a horizontal plane, and that when the shelf is lowered and disposed in a vertical plane the lugs will be parallel to the side walls of the depending arm of each slot. It will be obvious, of course, that the angle of one arm of the slot may be changed relative to 75 the other arm of the slot in order to secure the support of the movable member in a certain predetermined plane, or that the angle of the lug 16 relative to the plane of the movable element may be changed in 80 order to support it in a predetermined angular relation.

The two elements which constitute my improved supporting means may be readily formed by casting though I do not wish to 90 limit myself to this manner of forming these elements.

In practice the device has been found to be very effective and much simpler than other supporting means of like character 95 known to me.

Having thus described my invention, what I claim is:

A locking support of the character described including a member having an attaching portion and a head, the head being formed with an angular slot having uniform width, the arms of the slot extending in diverging relation, and a second member coacting therewith having a laterally projecting lug being approximately rectangular in cross section, the lug having a thickness approximately equal to the width of the slot and a width less than the length of either arm of the slot but greater than the width 110 of the slot whereby said second-named member will be held from rotation when disposed entirely in either arm of the slot.

In testimony whereof I hereunto affix my signature in the presence of two witnesses. 115

SAMUEL WEINBERG.
